[57] CLAIM

The ornamental design for a bird feeder, substantially as shown and described.

DESCRIPTION

FIG. 1 is a front elevational view of a bird feeder showing my new design;
FIG. 2 is a bottom plan view thereof;
FIG. 3 is a right side elevational view thereof, the left side being a mirror image of the right side shown;
FIG. 4 is a cross sectional view taken on line 4—4 of FIG. 1; and
FIG. 5 is a top plan view thereof.

FIG. 1

FIG. 2

FIG.3

FIG.4
